HANDLE FOR FISHING ROD

Robert Mimeur, Sallanches, France, assignor to
Carpano et Pons, Clauses, France

Filed Oct. 15, 1969, Ser. No. 19,566

Claims priority, application France Apr. 17, 1969

Term of patent 14 years

Int. Cl. D22—05

U.S. Cl. D22—23

Fig. 2

Fig. 1

Fig. 3

In the drawing:

FIG. 1 is a front elevational view of a handle for fishing rod showing my new design.

FIG. 2 is a side elevational view thereof.

FIG. 3 is a side elevational view thereof showing the side opposite that of FIG. 2.

Portions of the fishing rod are shown in broken lines for purpose of illustration only.

I claim:

The ornamental design for a handle for a fishing rod, substantially as shown and described.
